EDWARD A. ALLEN, OF RUMFORD FALLS, MAINE.

METHOD AND MEANS FOR ELECTROLYZING SALINE SOLUTIONS.

1,109,311.

Specification of Letters Patent.

Patented Sept. 1, 1914.

Application filed January 6, 1912. Serial No. 669,792.

To all whom it may concern:

Be it known that I, EDWARD A. ALLEN, a citizen of the United States, and resident of Rumford Falls, in the county of Oxford and State of Maine, have invented certain new and useful Improvements in Methods and Means for Electrolyzing Saline Solutions, of which the following is a specification.

10 This invention has relation to cells for and methods of electrolyzing saline solutions for the production of chlorin and hydrates such as sodium hydrate or potassium hydrate.

15 The primary object of the invention is to prevent the absorption of the chlorin in the solution being electrolyzed.

On the accompanying drawing, Figure 1 illustrates a longitudinal section through a cell embodying the invention. Fig. 2 represents a transverse vertical section through the same. Fig. 3 represents a horizontal section immediately above the upper diaphragm, the diaphragm being broken away at the left end to show the supporting grid 25 which is located beneath it. Fig. 4 illustrates two of the carbon anodes and shows how their upper surfaces are fluted or grooved.

According to my invention, I propose to 30 employ two diaphragms which are separated to provide a space for the electrolyte, and through which the latter is caused to flow, such electrolyte consisting of brine, that is, water saturated with salt or potassium chloride, or other solution which may be electrolyzed. The anode, which is located on the outer side of one of the diaphragms, is formed of carbon blocks, whereas the cathode, which is located on the outside of the 35 other diaphragm, consists of a layer of mercury, with which the cations given off during the electrolyzation of the brine unite to form amalgam. Necessarily the diaphragms are arranged horizontally, the carbon anode 40 being underneath the lower diaphragm and the mercury cathode being above the upper diaphragm and completely covering it. The lower diaphragm is preferably formed of some material such as asbestos cloth through 45 which the electrolyte will percolate, not too freely and yet sufficiently to prevent the chlorin which is given off at the anode from passing through it to contact with the electrolyte in the space between the diaphragms. 50 Above the layer of mercury there is contained a body of water into which project

numerous conductors or electrodes which constitute the cathode of a primary cell consisting of the mercury and amalgam, the body of water, and the conductors or electrodes. The upper diaphragm is preferably relatively stiff, being made of asbestos cloth coated or impregnated with cement so as to be nearly impervious to the passage of liquor therethrough. If, however, it be made 60 of several untreated layers of asbestos cloth, the mercury itself will form a seal to prevent the passage of the electrolyte therethrough upward or the passage of the water therethrough downward.

In operation, the electrolyte is caused to flow through the space between the diaphragms, and, current being passed from the carbon anode to the conductors last referred to, the following action takes place:—The 75 saline solution is decomposed, chlorin being given off at the carbon anode and being carried away in any convenient manner, and on the surface of the upper diaphragm, where the layer of mercury rests, the metal, 80 which is liberated (i. e. sodium, potassium or the like), unites with the mercury to form an amalgam. The amalgam being lighter than the mercury, slowly rises to the top thereof, so that, when the amalgam 85 comes in contact with the water, the metal is freed and unites with the water, forming the hydrate of the metal, according to the well known formulæ, hydrogen being of course liberated. Sufficient hydrostatic 90 pressure is maintained with the electrolyte compartment to sustain the upper diaphragm with its weight of mercury and water.

Proceeding to a more detailed description 95 of the cell, the body thereof consists of a rectangular tank comprising a bottom wall *a*, end walls *a'* and side walls *a''*. The cell body may be of wood, slate or other suitable material. Upon the bottom of the cell body, 100 I place cross pieces *b* of wood, slate or other suitable material upon which rest two longitudinal carbon bars *c* which are connected by cylindrical carbon bars or conductors *d*, the latter being tapered as shown in Fig. 2. The 105 ends of these carbon conductors *d* project through the side walls of the cell body and are connected by bus bars or other suitable forms of conductors to which may be connected the conductors from the dynamo. 110 Resting upon the longitudinal bars *c* and connected thereto by carbon dowels *c'* are the

flat carbon plates *e* which constitute the anode of the cell. The upper faces of these anode plates are grooved or corrugated as illustrated in Fig. 3, the bottom walls of 5 said grooves being preferably inclined to the horizontal. Extending horizontally across the cell are the two diaphragms *f* and *g*, the former being supported in part by the upper faces of the anode plates. The dia- 10 phragms are separated by a grid consisting of a rectangular frame *h* having bars *h'* projecting from its sides across the cell, each cross bar terminating short of the opposite side of the frame so as to form a tortuous 15 path in which the electrolyte will flow. Preferably the side walls of the cell are divided in a horizontal plane so that the grid may be placed between the two sections thus formed, and the outer edges or margins of 20 the diaphragms are secured to the frame of the grid so as to constitute with it a removable unit. Between the edges of the dia- phragm and the adjacent surfaces of the cell body, I interpose strips of insulating ma- 25 terial as indicated at *i*. It will be seen from Fig. 1 that the cross bars *h'* of the grid are preferably diamond shaped in cross section. The space *j* between the two diaphragms I term the electrolyte compartment, the space 30 within the cell body below the lower dia- phragm indicated at *h* being designated the anode compartment, and the space *m* above the upper diaphragm *f* being called the cathode compartment. As previously stated, 35 the lower diaphragm *g* is preferably made of one or more layers of asbestos cloth through which the electrolyte, which is introduced into the electrolyte compartment, will percolate slowly. To retard the flow or 40 percolation therethrough, the diaphragm may then have a thin skin coat of, or be im- pregnated with, cement, asbestos fiber or the like. The upper diaphragm *f* rests upon the cross bars of the grid *h* and it is prefer- 45 ably made of one or more layers of asbestos cloth impregnated with cement.

Projecting into one end of the electrolyte compartment is an inlet pipe *n* leading from a standpipe *n'* into which the brine is de- 50 livered from any convenient source. The brine is maintained at a height in the stand- pipe to insure hydrostatic pressure in the electrolyte compartment sufficient to prevent the diaphragm *f* from sagging materially 55 between the cross bars of the grid under the weight of the mercury and the water. From the electrolyte compartment extends a goose- neck pipe *n*² to conduct away the impover- ished solution to some tank where it is again 60 supplied or enriched with salt. The electro- lyte flows constantly through the electrolyte compartment *j* and follows the tortuous path hereinbefore referred to. Above the upper 65 diaphragm *f* is a layer *o* of mercury, which in actual practice may be from one-half to

one inch thick and which is in contact with the entire upper exposed surface of said diaphragm. Above the mercury there is a body of water indicated at *p* into which project numerous terminals or electrodes *q* de- 70 pending from cross bars *r*. Each terminal consists of a thin plate of iron or copper extending across the cell, as shown in Figs. 1 and 2. The cross bars *r* are all connected to a suitable bus bar or other terminal from 75 which conductors lead to the dynamo. Wa- ter is introduced into the cathode com- partment of the cell through an inlet pipe *s* and the hydrate solution passes out through an overflow pipe *t*. The chlorin, which is 80 given off in the anode compartment, is con- ducted away by means of a pipe *u*, and such electrolyte as percolates through the lower diaphragm *g* is conducted away from the bottom of the anode compartment by a pipe 85 *v*, which is water sealed as indicated at *w*, so that the chlorin pipe *u* may be connected with a vacuum system.

I desire to call attention to the fact that there is no mechanical operation connected 90 with the cell except the delivery of the elec- trolyte and of the water to their several com- partments. The metal, which is given off in contact with the mercury cathode, forms amalgam, which, being of a less specific 95 gravity than the mercury, rises to the upper surface into contact with the water. A sec- ond electrolytic action thereupon takes place, producing an electric current as in a pri- 100 mary cell, and, as a result, the voltage re- quired to operate the cell as a whole is ma- terially reduced. The base metal (sodium, 105 potassium, etc.) being liberated from the mercury unites with the water and forms a hydrate. This action all occurs in the same 110 compartment of the cell.

Having thus explained the nature of my 115 said invention and described a way of con- structing and using the same, although without attempting to set forth all of the 120 forms in which it may be made or all of the modes of its use, what I claim is:—

1. The herein described process of elec- 125 trolyzing saline solutions, which consists in bringing a body of solution into contact with the inner confronting faces of opposed hori- 130 zontal diaphragms, passing a current of elec- tricity therethrough, liberating chlorin at an unimmersed anode outside of one of said diaphragms so that it is unabsorbed by said body of electrolyte, liberating the metal in 135 contact with the lower surface of a mercury cathode outside of and in contact with the other diaphragm to amalgamate with said mercury, and liberating the said metal at the upper surface of said cathode in the presence of water.

2. The herein described process of elec- 140 trolyzing saline solutions, which includes passing a current of electricity upwardly 145

- from an anode through such solution and through a horizontal diaphragm, a layer of mercury, and a body of water to a terminal electrode, all in the order named, liberating 5 the metal in said solution in contact with the under face of said cathode to amalgamate therewith, liberating said metal at the upper surface of said cathode in the presence of water to form a hydrate, and liberating 10 chlorin at a point below the body of saline solution and out of contact therewith.
3. In an electrolytic cell, the combination of horizontal confronting diaphragms forming an electrolyte compartment between them, a carbon anode below and in contact with the lower diaphragm, and a layer of mercury resting on the upper diaphragm and constituting the cathode.
4. An electrolytic cell, comprising a cell 20 body, separated horizontal diaphragms in said body forming a compartment between them for the electrolyte, an anode compartment below them, and a cathode compartment above them, an anode below and in contact with the lower diaphragm, a mercury cathode above the upper diaphragm and in contact therewith, and a body of water above and in contact with the cathode.
5. An electrolytic cell, comprising a body, 30 separated diaphragms forming a compartment for the electrolyte, a grid between said
- diaphragms, an anode on which the lower diaphragm rests, a mercury cathode covering the upper diaphragm, terminal electrodes, means for circulating electrolyte 35 through said electrolyte compartment, and means for supplying a body of water to said cell to contact with said terminal electrodes and said mercury cathode.
6. An electrolytic cell comprising a cell 40 body, a substantially flat anode having grooves or passageways, a diaphragm contacting with the upper face of the anode, a second diaphragm parallel to and separated from the other diaphragm to form a separate 45 compartment for the circulation of the electrolyte, a mercury cathode resting upon the upper diaphragm, spacing devices between the two diaphragms, terminal electrodes above and separated from the mercury cathode, provisions for circulating electrolyte through the said compartment, and provisions for supplying water to the cell body, to provide a body of water in contact with said cathode and said terminal electrodes, 50 and for removing hydrate from said cell.
- In testimony whereof I have affixed my signature, in presence of two witnesses.
